RAPID REVOLVER LOADER

Thomas A. Milmore, Brooklyn, N. Y.

Application April 3, 1933, Serial No. 664,050

5 Claims. (Cl. 42--89)

The invention relates to devices for simultaneously charging all the chambers in a revolver. It is a further improvement on the revolver loader shown in Letters Patent No. 1,891,437 which were

5 granted to me December 26th, 1932.

The main object of the present invention is, like the object of my previous invention, to provide a device which makes it possible to completely load or reload a revolver in a very short 10 space of time and without any previous practice or skill. In addition the present invention has for one of its objects to provide a revolver loader which will hold a sufficient number of cartridges to load a revolver twice. Another object is to 15 provide means whereby the insertion of the cartridges in the loader, as well as the insertion of the filled loader in its casing, is greatly facilitated.

These and various other objects and advantages will be readily understood from the following description and from the accompanying drawings of preferred embodiments of the invention in which, however, modifications may be made without departing from the scope of the appended claims. In the drawings

25 Fig. 1 is a rear view of a certain embodiment of the loader, shown straightened out;

Fig. 2 a top view of same;

Fig. 3 another top view, showing the loader in its normal position and with the cartridges re- 30 moved;

Fig. 4 still another top view, showing how the cartridges are transferred from the loader to the cylinder of a revolver;

Fig. 5 a cross-sectional side view, showing the 35 loader in its casing;

Fig. 6 a rear view of the casing, showing the loader inserted therein;

Fig. 7 a front view of a modification of the 40 loader, shown straightened out;

Fig. 8 a top view of same, shown in its normal position;

Fig. 9 another top view, shown straightened out;

Fig. 10 a top view of another modification, 45 shown in its normal position; and

Fig. 11 another top view of same, shown straightened out.

Referring first to Figs. 1 to 6, the device comprises a flat spring 1 which is provided with a finger grip 2 and on which two rows of cartridge clips 3 and 4 are formed or secured in any suitable manner. The clips are spaced parallel with the axis of the spring so that the cartridges 5 and 6 will project over both edges of the spring

and so that the cartridge heads 7 and 8 will be held between the oppositely-disposed clips. This is plainly illustrated in Fig. 1.

The clips extend only a sufficient distance around the cartridges to hold these securely and a rather large space is therefore left between their ends. Furthermore, the clips are so located that these spaces point away from the finger grip so that the cartridges may be readily removed from the clips by a pull on the finger grip.

In Fig. 1 the spring is shown straightened out but its normal position is that shown in Fig. 3. The spring normally tends to form a hoop; the end 9 abutting against the first clip. When in this position, the clips, and consequently the cartridges contained therein, align with the chambers in the cylinder of the revolver. The number of clips being equal to the number of chambers.

As it would be inconvenient and cumbersome to carry the loader in its normal position, a casing 10 is provided in which it is inserted and carried in its straight position. This casing is preferably made of leather and carried in a hip pocket.

To facilitate the insertion of the cartridges in the loader and to likewise facilitate the insertion of the filled loader in the casing, a loading bar 11 is provided. This bar has a hook 12 at one end which fits over the end 9 of the spring 1, and is provided with a clamp 13 at its other end. When it is desired to insert cartridges in the loader, the hook 12 is slipped over the end 9 and the spring 1 is straightened out. The operator now holds the finger grip 2 and the clamp 13 between his fingers and so keeps the spring in the straight position. While in this position the cartridges can readily be inserted in the clips. It likewise holds the spring straight while it is being inserted in the casing. In addition, the clamp 13 secured the bar to the casing, as well as securing the casing to the pocket in which it is carried.

It will readily be understood that the loader instantly assumes the position shown in Fig. 3 when withdrawn from the casing. If the ends of the cartridges 6 are now inserted in the chambers of the cylinder 14 until the spring 1 rests on the cylinder and the finger grip is pulled in the direction indicated by the arrow in Fig. 4, the cartridges 6 will be released from the clips and drop in to their respective places in the cylinder. As previously explained, the release of the cartridges is made possible by the large spaces between the ends of the clips and by the posi-

tion of these spaces. While the cartridges are being released the cylinder rotates in the direction of the curved arrow. As illustrated in Fig. 4, three of the cartridges 6 are shown released from their clips, while the remaining cartridges 5, are still engaged.

After the cartridges 6 have been fired, the cylinder is emptied in the ordinary manner and, by turning the loader upside down, the cartridges 5 may be transferred to the cylinder in the same manner as just described. It will be noted that the heads 7 and 8 of the cartridges fit snugly between the clips 3 and 4 and thus prevent longitudinal displacement of the cartridges. After one of the sets of cartridges has been removed from the loader, the other set is still prevented from being displaced by their heads engaging with the now empty clips. It will also be noted that when the loader is withdrawn from the casing the bar 11 remains in the casing and, by clamping the casing to the pocket, prevent it from being pulled out.

A modification, the principle of which is the same as in the device just described, is shown in Figs. 7, 8 and 9. In this modification a plurality of links 15 are substituted for the spring 1. These links are hinged at 16 and actuated by springs 17 which tend to hold the device in the position shown in Fig. 8.

In the modification shown in Figs. 10 and 11, two sets of cartridge clips are secured on each of the links 18 which are hinged at 19 and actuated by springs as in the modification just described.

While I prefer to use springs for positively actuating the links, these springs might be omitted as the links may be formed in to the positions shown in Figs. 8 and 10 by a quick toss of the wrist. While I have shown ordinary cartridges on the drawings, it is evident that the device may as readily be used for other kinds of cartridges, for example, tear-gas cartridges.

Having described my invention and its object, what I claim as new and wish to protect by Letters Patent is:

1. A device of the class described comprising a spring-actuated body part having a normal tendency to form a hoop, a finger grip associated with said body part, two sets of oppositely-disposed cartridge clips secured on said body part, a casing in which the device is carried in its extended

position, and a bar for holding the body part in its extended position while the cartridges are being inserted in the clips and while the device is being inserted in the casing.

2. A device of the class described comprising a spring-actuated body part having a normal tendency to form a hoop, a finger grip associated with said body part, two sets of oppositely-disposed cartridge clips secured on said body part, a casing in which the device is carried in its extended position, a bar for holding the body part in its extended position while cartridges are being inserted in the clips and while the device is being inserted in the casing, and a clamp formed on said bar for securing it to the casing.

3. A device of the class described comprising a spring-actuated body part having a tendency to form a hoop, a finger grip associated with said body part, two sets of oppositely-disposed cartridge clips secured on said body part, a casing in which the device is carried in its extended position, a bar for holding the body part in its extended position while cartridges are being inserted in the clips and while the device is being inserted in the casing, and a clamp associated with said bar for securing it to the casing and for securing the casing to the pocket in which it is carried.

4. A device of the class described comprising a spring-actuated body part having a normal tendency to form a hoop, a finger grip associated with said body part, a plurality of cartridge clips secured on said body part, a casing in which the device is carried in its extended position, a bar for holding the body part in its extended position while cartridges are being inserted in the clips and while the device is being inserted in the casing, and a clip formed on said bar for securing it to the casing.

5. A device of the class described comprising a spring-actuated body part having a normal tendency to form a hoop, a finger grip associated with said body part, a plurality of cartridge clips secured on said body part, a casing in which the device is carried in its extended position, a bar for holding the body part in its extended position while cartridges are being inserted in the clips and while the device is being inserted in the casing, and a clip formed on said bar for securing it to the casing and for securing the casing to the part in which it is carried.
